UNITED STATES PATENT OFFICE.

JOHN R. YOUNGBLOOD, OF NEW ORLEANS, LOUISIANA.

TELEGRAPH TRANSMITTER.

Application filed April 16, 1926. Serial No. 102,500.

This invention relates to improvements in telegraph keys or transmitters, and an object of the invention is to provide a novel form of manipulator which is movable a relatively short distance for rapid interruption of the circuit to transmit dots, and a slightly longer distance in the opposite direction to interrupt the circuit more slowly in the transmission of dashes.

Other objects and advantages appear in the following specification, reference being had to the accompanying drawings, in which

Figure 1 is a plan view of the improved transmitter,

Figure 2 is a longitudinal section taken substantially on the line 2—2 of Figure 1,

Figure 3 is a cross section on the line 3—3 of Figure 1,

Figure 4 is a detail cross section on the line 4—4 of Figure 1,

Figure 5 is a horizontal section taken on the line 5—5 of Figure 2,

Figure 6 is a detail cross section taken on the line 6—6 of Figure 5,

Figure 7 is a side elevation of the improved manipulator,

Figure 8 is a diagrammatic plan view illustrating the position of the manipulator when closing the circuit to make dots,

Figure 9 is a detail vertical section illustrating the axially aligning positions of the pivot bar and finger bar when sending dots,

Figure 10 is a diagrammatic plan view showing the position of the manipulator when closing the circuit to transmit dashes,

Figure 11 is a detail vertical section illustrating the disalignment of the axes of the pivot and finger bars when sending dashes,

Figure 12 is a detail inverted perspective view of the instrument illustrating how connection is made between the large and small underplate.

In carrying out the invention provision is made of an insulating base 1 which, by preference, is made of a heavy piece of glass, although other known insulating material may be used if found desirable. Glass, as an insulator, has the advantage of being a perfect non-conductor of electricity. It is not affected by dampness as are rubber or fibrous substances such as are commonly used.

Three rubber buttons 2 support the base in spaced relationship to the table. Two of these are located at the corners at the rear

of the base, one being located in the center near the front. A screw 3 which secures the front button 2 to the base 1 also serves to hold a mute 4 in position upon the base. The mute is substantially U-shape, one of the legs 5 serving as the mounting for a stop 6 with which the extremity of the vibrator 7 engages at times.

Situated beneath the glass base 1 is a brass or other metallic underplate 8 which, because of its relative size is herein known as the large underplate. Situated beneath the underplate 8 is the underplate 9 which, because of its relatively small size is herein known as the small underplate. These plates are spaced apart from each other and must be considered as components of opposite sides of an electrical circuit. For illustration, the large underplate 8 is herein regarded as being electrically positive while the small underplate 9 is regarded as electrically negative.

A hole 10 in the front end of the underplate 8 (Figs. 1, 2 and 5) admits the screw 3 and the washer 11 thereof without making electrical contact. The rear corners of the large underplate are cut away at 12 (Figs. 1 and 5) to avoid making electrical contact with the nut 13 which holds the rear rubber button 2 in place upon the small underplate 9. A metallic connection between the plates 8 and 9 would produce a short circuit which must not occur while the transmitter is in condition for operation.

While dealing with this point reference may be had to Figure 12. The small underplate 9 has a forward extension or lip 14 which is sufficiently resilient for the following purpose: In order that the transmitter may be connected in the proper electrical circuit, a wedge consisting of plates 15 and 16, separated by insulating means 17, is inserted between the lip 14 and the large underplate 8. The respective plates 15 and 16 have electrical connection with wires 18 and 19 which, in order to bear out the former example, are regarded as being positive and negative respectively. The small underplate carries a lever 20 which is pivotally mounted to the plate 9 alone as at 21. This lever is capable of being moved into engagement with the head of a screw 22 which, having electrical connection with the large underplate 8, will serve to cause a short circuit between the plates 8 and 9.

Connected with the large underplate 8 are the front and rear brackets 23 and 24 which respectively have pairs of posts 25 and 26 upon which screws are mounted. A screw 27 (Fig. 2) connects the front bracket with the large underplate 8 and secures said bracket upon the base. The screw 22 of similar purpose has been referred to. The screw 28 of one of the posts 25 is a contact with which the spring contactor 29 upon the vibrator 7 coacts when transmitting dots (Fig. 9). The screw 30 of one of the posts 26 is a contact with which the diametrically opposite spring contactor 31 of the vibrator 7 coacts when transmitting dots (Fig. 9).

The screw 32 of the other post 26 is a contact with which the rigid but adjustable contactor 33 of the finger bar 34 coacts when transmitting dashes (Fig. 10). An arch 35 provides the principal mounting for the manually movable element generally known as the manipulator. The manipulator is shown alone in Figure 7. It comprises the vibrator bar 7 previously mentioned. The rear end of this bar, in addition to carrying the contactor springs 29 and 31, has a rather broad but quite flexible leaf spring 36 with which connection is made to a pivot bar 37. If the manipulator were separated, the vibrator 7 and pivot bar 37 would remain together due to the connection of the leaf spring 36.

A groove 38 extending longitudinally of the pivot bar 37 from end to end receives the beveled edge 39 of the finger bar 34. A rearward extension of the finger bar carries the contactor 33, mentioned before, as well as insulating finger tips 40. Rocking of the finger bar 34 relative to the pivot bar 37 occurs when the manipulator is moved to the left (Figs. 10 and 11) in transmitting dashes.

A saddle 41, secured in place upon the finger bar 34 by means of a set screw 42, has a notch 43 on the underside corresponding with a notch 44 in the lower edge of the finger bar to make room for the head of the lower pivot screw 45. This pivot screw is rigidly fixed in position upon the pivot bar 37, but the beveled point thereof is capable of motion in a recess 46 in the bottom plate 47 of the arch 35.

A recess 48 in the upper side of the saddle 41 receives the beveled point of an upper pivot screw 49 carried by the bend of the arch. The two pivot screws, the finger bar 34 and the pivot bar 37 are in vertical axial alignment, and remain so when the manipulator is rocked to the right in transmitting dots. But when rocking the manipulator to the left to transmit dashes the foregoing parts move out of axial alignment (Fig. 11) by virtue of a relative rocking of the finger and pivot bars 34 and 37.

For the dot transmitting function a stop

screw 50 performs the important purpose of keeping the finger and pivot bars in the above vertical axial alignment by engaging the right side of the pivot bar (Figs. 8 and 9) thus providing an additional mounting upon which the pivot bar partakes of pivotal motion. For the latter dash transmitting function the forward extremity of the pivot bar 37 engages a stop screw 51 which thereupon serves as a pivotal point 75 upon which the pivot bar turns to a disaligning position in reference to the vibrator (Fig. 10). This disalignment is permissible by the flexible leaf spring 36, the disalignment being compensated for by the rockable mounting of the finger bar upon the pivot bar along the groove 39 of the latter.

The stop screw 50 is adjustably fixed in the right leg of the arch 35. One of a pair of forwardly extending arms 52 and 53 carries 85 the stop screw 51. The other arm 53 carries a screw 54 which is the complement of the screw 51. Tension of a light spring 55 bearing against one side of the pivot bar 37 is adjusted by a screw 56 carried by the arm 90 52. A weight 57, slidably adjustable along the vibrator 11, provides for regulating the speed of the manipulator.

The bottom plate 47 of the arch 35 is connected with the small underplate 9 by means 95 of screws 58.

Inasmuch as the arch must be insulated from the large underplate 8, the screws 58 and the notch 59 (Fig. 5) that hold the small underplate in spaced relationship with the glass base 1 pass through and occupy holes 60 in the large underplate.

The operation may be readily understood. Upon desiring to place the transmitting instrument in circuit for operation, the wedge, illustrated in Figure 12, is inserted between the large under plate 8 and the front extension or lip 14 of the small underplate 9. The wedge is composed of plates 15 and 16, insulated from each other, and respectively 110 connected with the positive and negative wires 18 and 19.

The front and rear post brackets 23 and 24 (Figs. 1 and 2) are electrically connected with the large underplate 8 and may 115 therefore be identified with the positive side of the circuit. The connection is made by means of screws 27 and 22 which serve the additional purpose of holding the brackets down upon the glass base 1. The various 120 posts 25 and 26 may be made separate, rather than make them integral with brackets as illustrated, but in such event they would have to be separately connected with the large underplate 8. The mute 4 has no electrical 125 connection with either of the underplates.

The arch 35 is electrically connected with the small underplate 9 by means of the screws 58 and may therefore be identified with the negative side of the circuit. The 130

entire manipulator is carried by the arch 35 and may therefore also be identified with the negative side of the circuit. The stop screw 54 (Fig. 1) limits the distance that the spring 55 may press the manipulator and the manipulator therefore normally assumes the position wherein the various contactors are out of engagement with the associated contact screws. The lower and upper pivot screws 45 and 49 are normally in vertical axial alignment as seen in Figure 3. The two actions of the instrument in telegraphing should be understood.

Transmitting dots: The electrical circuit is made and broken in rapid succession when transmitting dots, and in view of the rapidity of the action, it is desirable to reduce the motion of the manipulator to the minimum. The insulated finger tip 40 is pressed to the right (assuming that the operator is facing the finger piece) whereupon the manipulator is swung as a whole upon the lower and upper pivot screws 45 and 49 (Fig. 8).

This unified swinging occurs by virtue of the fact that the stop screw 50 is in normal contact with the side of the pivot bar 37. The connection of the finger bar 34 with the pivot bar 37 along the edge 39 and groove 38 affords a loose connection between the elements mentioned, and advantage is taken of this circumstance as presently appears. But when transmitting dots, this connection remains quite rigid, and the function is obtained by the thumb screw 50.

The lower and upper pivot screws 45 and 49, as well as the intermediate parts of the manipulator, therefore remain in vertical axial alignment (Fig. 9) when operating the instrument to transmit dots. The foregoing motion of the finger piece 40 to the right causes the spring contactors 29 and 31 to engage the associated contact screws 28 and 30 thereby closing the circuit which is supposed to be normally open between the underplates 8 and 9. The two spring contactors 29 and 31 provide a double stop contact, which, while desirable, is not essential to the efficient operation of the instrument. One or the other of the spring contacts may be omitted without the omission of any function.

Transmitting dashes: The electrical circuit is made and broken more slowly when transmitting dashes than when sending dots. The finger tip 40 is pressed to the left, and the slightly increased distance through which the finger bar 34 must move before contact is made adds something to the time interval in making and breaking the circuit. The action is quite different from that in sending dots. The vibrator 7 of the manipulator, and the pivot bar 37 are connected by the leaf spring 36 which is compelled to twist or flex slightly when the for-

ward extremity of the vibrator engages the abutment 6 under pressure of the finger piece 40 to the left (see Fig. 10).

At this time the right side of the forward extremity of the pivot bar 37 engages the stop screw 54, and this point thereby becomes a fulcrum on which the pivot bar moves. Inasmuch as the movement of the pivot bar is not restrained by a stop screw as was the case at the stop screw 50 when transmitting dots it follows that the formerly straight pivot screw 45 rocks slightly in recess 46 in the bottom plate 47, and assumes an angled relationship to the bottom plate as shown in Figure 11.

The finger bar 34 follows the pivot bar, in fact, it being the pressure applied to the finger bar that produces the foregoing action of the pivot bar. The forward end of the pivot bar 37 being restrained by the stop screw 54 it follows that the finger bar 34 will rock in relation to the pivot bar, as shown in Figure 11. The rocking occurs along the edge 39 and groove 38. It also occurs at the recess 48 of the panel 41 in relation to the upper pivot screw 49. It is readily seen that the disalignment of the pivot bar 37 from the vibrator 7 must twist the leaf spring 36, and the tension set up in the leaf spring, assisted by the pressure of the light spring 55, will return the pivot bar 37 and the vibrator 7 to the original positions when finger pressure is released.

Upon movement of the lever 20 into engagement with the head of the screw 22 (Figs. 2 and 12) the large and small underplates 8 and 9 become short circuited so that the manipulator is temporarily deprived of its function. The foregoing short circuiting of the transmitter is desirable at times in practice.

In addition to the fundamental purpose of making it possible to transmit electrical impulses at high speeds, there is an object in the specific construction of the transmitter. It is observed that only one insulating element is employed, namely, the glass base 1. The numerous insulating washers, etc. usually seen in instruments of this character, are omitted. The metallic contents are about evenly divided between the so-called positive and negative elements, all parts that are identified with the positive side of the circuit being electrically connected with the underplate 8 and all parts identified with the negative side of the circuit being connected with the underplate 9. The manipulator (Fig. 7) which is relatively large is connected with the relatively small plate 9, while the post brackets 23 and 24, which are relatively small, are connected with the large underplate 8. The two elements are therefore about evenly divided, and the balance thus afforded is thought to have advantages.

Upon moving the finger tip 40 to the left,

as in transmitting dashes, the rigid contactor 33 is brought into engagement with the contact screw 32, thereby completing the current path from the plate 8 to the 5 plate 9 and in turn completing the electrical circuit.

In conclusion reference is made to a feature of the invention that is regarded as an advantage in practice. The making of a 10 few changes will prepare the transmitter so that left hand operation will be facilitated. The contactors 23, 31 and 33 are taken off and mounted upon the manipulator on the side opposite to which they now appear. The screws 50 and 56 (Fig. 3) are 15 reversed in position on the arch. The spring 35 goes with the screw 56. The stop 6 is placed on the other side of the mute 4. These changes adapt the transmitter to left 20 hand operation without any other change in the manipulator itself.

While the construction and arrangement of the improved telegraph transmitter is that of a generally preferred form, obviously modifications and changes may be 25 made without departing from the spirit of the invention or the scope of the claims.

I claim:—

1. A transmitting instrument comprising 30 a single insulating base, a relatively large metallic plate applied to the underside of the base and being connectible with one side of a circuit, relatively small brackets mounted upon the base and in connection with said 35 plate, a relatively large metallic manipulator having contactors, a relatively small plate situated on the underside of the base, means through which said manipulator is in electrical connection with said relatively 40 small plate, the foregoing relative size of parts establishing a relatively even division of metal between the parts on the respective sides of the circuit, and contacts carried by said brackets with which said contactors are 45 engageable to close the circuit upon operation of the manipulator.

2. A transmitting instrument comprising 50 a single insulating base, a metallic plate co-extensive with the base and situated on the underside thereof, a relatively small under-plate disposed beneath said first plate, contact brackets mounted upon the base and being connected with said first plate, a metallic manipulator, an arch mounted upon 55 the base being connected with said relatively small plate, means included in said connection holding the relatively small plate in spaced relationship with the base and said first plate, said first plate having holes to 60 admit said means, means for pivotally mounting the manipulator within the arch, contactors carried by the manipulator, and contacts carried by said brackets.

3. A transmitting instrument comprising 65 a manipulator having a contactor on each of

opposite sides, a finger bar by which one of the contactors is carried, said finger bar being part of the manipulator, means providing a pivotal mounting for the manipulator, a contact relatively close to one of the 70 contactors requiring relatively small rocking motion of the manipulator for effecting an engagement, a contact relatively distant from the other contactor, and means permitting relative motion of the finger bar to 75 effect engagement of said contact by the contactor on the finger bar when the manipulator is given a relatively large rocking motion.

4. A transmitting instrument comprising 80 a manipulator which includes pivot and finger bars, lower and upper pivot screws for the pivot and finger bars by which the manipulator is pivotally supported, means embodied in the connection between the 85 pivot and finger bars permitting a relative motion upon rocking the manipulator in one direction, and means in position to contact the pivot bar when rocking the manipulator in the opposite direction, keeping the said 90 pivot pins and bar in vertical axial alignment.

5. A transmitting instrument comprising 95 a manipulator including pivot and finger bars, lower and upper pivot screws for the respective bars by which the manipulator is pivotally supported, a double bevel along one edge of the finger bar being seated in a groove in the pivot bar providing a connection 100 permitting relative motion of the bars when rocking the manipulator in one direction, and means in position to engage the pivot bar to prevent said relative motion of the bars keeping them in axial alignment with the pivot screws when rocking the 105 manipulator in the opposite direction.

6. A transmitting instrument having an arch provided with a fixed pivot screw and a recess, a manipulator comprising a finger bar and a pivot bar, a saddle on the finger 110 bar having a recess receiving the point of the pivot screw, a pivot screw fixed upon the pivot bar having the point seated in the recess of the arch, a double bevel along 115 one edge of the finger bar seated in a groove of the pivot bar permitting relative motion of the bars when rocking the manipulator in one direction, said saddle then moving in respect to the fixed pivot screw and the second pivot screw moving in respect to the 120 arch recess thereby disaligning the elements mentioned, and means in position to engage the pivot bar upon rocking the manipulator in the opposite direction preventing said relative motion of the bars and maintaining 125 said elements in axial alignment.

7. A transmitter having a pair of fixed contacts, a manipulator including a vibrator having a contactor disposed relatively close to one of the contacts and engageable with 130

the contacts upon a relatively small motion of the manipulator in the direction thereof, a finger bar being part of the manipulator and having a contactor relatively distanced 5 from the other contact and engageable therewith upon a relatively large motion of the manipulator in the direction thereof, and means interposed in the connection between the finger bar and vibrator being subject to 10 flexure so that said relatively large motion can be accomplished.

8. A transmitting instrument having a pair of fixed contacts, a manipulator including a vibrator having a contactor relatively close 15 to one of the contacts and engageable therewith upon a relatively small motion of the manipulator in the direction thereof, a finger bar being part of the manipulator and having a contactor relatively distanced from the 20 other contact and engageable therewith upon a relatively large motion of the manipulator, means pivotally supporting the manipulator for the foregoing motion thereof, means interposed in the connection between the finger 25 bar and vibrator being subject to flexure whereupon a disalignment of the pivot means occurs when accomplishing said relatively large motion, and means in position to prevent said flexure when accomplishing said 30 relatively small motion, said means at the same time keeping the pivot means in alignment.

9. A transmitting instrument comprising a manipulator including a finger bar, a pivot 35 bar and a vibrator; an arch having a fixed pivot screw and a recess, a saddle carried by the finger bar having a recess receiving the point of the pivot screw, a pivot screw fixed upon the pivot bar having the point seated 40 in the contactors mounted on diametrically

opposite sides of the vibrator, fixed contacts with which they are engageable, flexible means connecting the vibrator and pivot bar, means in position to engage the pivot bar upon motion in one direction of the manipulator to effect engagement preventing flexure of said pin and keeping the pivot structure in axial alignment, a contactor carried by the finger bar, and a fixed contact with which 45 said contactor is engageable upon movement 50 of the manipulator in the opposite direction, said engagement being accomplished by flexure of said flexible means, a disalignment of the pivot and finger bars and a resulting rocking of the saddle in respect to the pivot 55 screw and a rocking of the pivot screw of the pivot bar in respect to the arch recess.

10. A transmitting instrument comprising a manipulator which consists of a vibrator, a pivot bar and a finger bar; a rockable 60 mounting for the manipulator, a bevel along one edge of the finger bar being seated in a groove in the pivot bar, a leaf spring joining the pivot bar with the vibrator, means in position to engage the pivot bar upon 65 motion of the manipulator in one direction serving as a fulcrum for the pivot bar and keeping the parts of the manipulator in alignment with the pivotal mounting, and means in position near that end of the pivot 70 bar and its connection with the vibrator being engageable by the pivot bar to prevent movement of the vibrator in the other direction serving as a fulcrum upon which the pivot bar is disaligned from the vibrator 75 with an accompanying flexing of the leaf spring, said pivotal mounting being yieldable to compensate for said disalignment.

JOHN R. YOUNGBLOOD.
